UNITED STATES PATENT OFFICE.

GEORGE E. ALEXANDER AND RALPH W. ALEXANDER, OF NEWPORT, NEW HAMPSHIRE.

REINFORCED BOW FOR RAKES.

1,383,182.

Specification of Letters Patent. Patented June 28, 1921.

Application filed July 31, 1918. Serial No. 247,586.

To all whom it may concern:

Be it known that we, GEORGE E. ALEXANDER and RALPH W. ALEXANDER, citizens of the United States, residing at Newport, 5 in the county of Sullivan and State of New Hampshire, have invented certain new and useful Improvements in Reinforced Bows for Rakes, of which the following is a specification.

10 This invention relates to new and useful improvements in hand rakes and the primary object of the invention is to provide a new and improved type of bow that is provided with a reinforcing means that greatly 15 strengthens the same and increases its durability and efficiency. The type of bow to which this invention is applicable is of the conventional type, that is ordinarily formed of a tubular metal member that is connected 20 with the head of the rake, and our improvement comprises a reinforcing bow which is positioned within the same so as to strengthen the bow and prevent it from becoming weakened or bent during the rough usage to 25 which these devices are subjected.

Another object of the invention is to provide a device of this character which is easily and simply constructed, inexpensive to manufacture, and one which will be very efficient 30 in operation.

With these and numerous other objects in view, our invention consists of the novel features of construction, combination and arrangement of parts which will be herein referred to and more particularly pointed out 35 in the specification and claim.

In the accompanying drawings:

Figure 1 is a perspective of the rake,

Fig. 2 is a detailed plan view of one end 40 of the rake head showing the bow portion partly in section, and

Fig. 3 is a transverse section through the bow.

In describing our invention, we shall refer 45 to the drawings in which similar reference characters designate corresponding parts throughout the several views.

The numeral 1 designates the head portion of a garden rake of the conventional type, 50 having projecting teeth 2, and connected with said head is the conventional type of handle 4. This construction is of the type

usually employed in devices of this character, and the head is reinforced on the handle by a plurality of bow members designated 55 by the numeral 3, arranged as is clearly shown in Fig. 1 of the drawings. Any number of these bows may be employed according to the size of the rake and the bows 3 are commonly formed of metal but in the conventional construction are hollow. 60

Our new and improved reinforcing means relates solely to the bows 3, and comprises a wooden core 7 adapted to be positioned within the bows 3 as is clearly shown in Fig. 2 of 65 the drawings. The wooden core 7 entirely fills the interior of the hollow bows 3 and when positioned therein forms a close connection as is clearly illustrated in Fig. 3 of 70 the drawings.

This wooden reinforcing core greatly increases the durability of a device of this character as it strengthens the hollow bows and prevents them from becoming broken or bent when subjected to rough usage as 75 these devices are liable to. Heretofore, the hollow metal bows have been found impractical, owing to their frailty and liability to become broken or bent, but by the insertion of the wooden reinforcing cores therein, this 80 objection is overcome with no material increase of the weight of the device. Lightness is a most essential feature in this type of agricultural implement, and this improvement overcomes a most objectionable feature without detracting from the usefulness or practicability of the article. 85

From the foregoing description, taken in connection with the accompanying drawings, it is thought that a clear and comprehensive understanding of the construction, combination and arrangement of parts of this device may be easily had, and while we have shown and described the device as embodying a specific structure, we desire that 90 it be understood that such changes may be made in said structure as do not depart from the spirit and scope of the invention as claimed. 95

Having fully described our invention, 100 what we claim as new, and desire to secure by Letters Patent, is:

The combination with a rake head having a handle secured thereto; of a bow therefor

composed of a substantially semi-circular, tubiform, metal member having a reinforcing core completely filling said member and extending throughout the entire length thereof, said reinforced bow extending through said handle and having its ends extending through said head, said core avoid-

ing breakage or distortion of the bow throughout its length and at its connection with the handle and the head. 10

In testimony whereof we affix our signatures hereto.

GEORGE E. ALEXANDER.
RALPH W. ALEXANDER.
